[57] **CLAIM**

The ornamental design for a combined ceiling fan and light with balloon decoration, as shown and described.

DESCRIPTION

FIG. 1 is a side elevational view of a combined ceiling fan and light with balloon decoration showing my new design, the opposite and adjacent sides being mirror images of that shown, and the broken-line showing of mounting hardware being for illustrative purposes only and forming no part of the claimed design;

FIG. 2 is a top plan view thereof;

FIG. 3 is a bottom plan view thereof; and,

FIG. 4 is a bottom perspective view thereof.
